HIP AND BUTTOCKS EXERCISING MACHINE

Robert Clarke, Pacific Beach, Calif., assignor to Paramount Health Equipment Corp., Los Angeles, Calif.

Filed Aug. 13, 1974, Ser. No. 496,923

Term of patent 14 years

Int. Cl. D21—02

U.S. Cl. D34—5 K

FIG. 2.

FIG. 1 is a right front perspective view of a hip and buttocks exercising machine, showing my new design; and FIG. 2 is a left rear perspective view thereof.

I claim:

The ornamental design for a hip and buttocks exercising machine, as shown.
